13 Claims. (Cl. 73—192)

(Granted under Title 35, U.S. Code (1952), sec. 266)

The invention described herein may be manufactured and used by or for the Government of the United States 10 of America for governmental purposes without the payment of any royalties thereon or therefor.

This invention relates to steam quality and condition indicators and more particularly to a device for measuring the moisture content of steam in a pipe when the moisture content is varying from zero to 50% under transient conditions where the full range of the variable occurs in two seconds.

In the case of the steam catapult, the moisture content of the steam should be known and minimized in order to limit erosion by the entrained water, to provide for the efficient use of steam water, and to reduce pressure lags due to flow friction.

The steam quality indicator is designed to measure the steam quality in a 6 or 12 inch diameter pipe where the pressure varies from 500 to 300 p.s.i.g., the moisture content varies from 0 to 50%, the steam flow rate is 0 to 700 lbs. per second, and the temperatures are the saturation values.

In the past calorimeters such as the separating, throttling, or superheating type have been used which involve collecting a representative steam sample and separating and measuring the steam and water. The major difficulty seems to be one of collecting a representative sample under the varying flow conditions during a two second period. Furthermore if a multiple throttling system were used where the steam samples are throttled into a plurality of expansion chambers (say 20 over the 2 second period), the limited moisture range of the throttling measurement of about 7% would require a second moisture measurement such as that given by a separating or superheating calorimeter.

The primary object of the present invention is to provide a system whereby the density of the steam is continuously measured by means of fast electrons (beta-rays), the pressure of the steam is measured, and the steam quality is automatically calculated and recorded without any limitation as to moisture content, steam flow rate, or sampling problems. The condition of superheated steam (its temperature) could be determined in a similar manner.

Wet steam is steam generated with a certain portion of entrained liquid water dispersed therein in minute droplets.

Steam quality expressed in percent is defined by

$$Q = \frac{M_v}{M_v + M_l} \times 100 \quad (1)$$

where M_v is the mass of vapor and M_l is the mass of the liquid of a given mixture of liquid and vapor. If we measure the quantity "density" of the water substance (liquid and vapor) by transversing a given volume of the material,

$$Q = a \frac{D_v}{D_{vl}} \times 100 \quad (2)$$

where D_{vl} is the mean density and a is a constant depending on geometrical considerations of the path. We will, as is usually done, assume that thermodynamic equilibrium exists with regard to temperature, pressure, and equi-partition of energy. The quantity M_v is then determined from a measurement of pressure and the

2

knowledge that the vapor is saturated at this pressure, in the fixed volume. The mass of 100% saturated steam filling the entire volume is related to the actual mass of dry steam in a volume of the mixture by

$$M_{vp} = M_v \left(\frac{V_v}{V_v - V_l} \right) \quad (3)$$

where V_v is the volume occupied by the vapor and V_l the volume occupied by the liquid. In the most unfavorable condition of 50% moisture, the term

$$\frac{V_v}{V_v - V_l}$$

has a value of about 1.01 so that for our purpose we may assume $M_{vp} = M_v$ without introducing an error of more than one part in 100 in the value of quality computed from Equation 1. It is of further interest to note FIG. 5 which is a plot of the density of saturated steam as a function of pressure. This is seen to be a straight line over the range of interest. It is in fact a very good straight line through the origin, and follows the formula $D_{vp} = .00216P$, where D_{vp} is the density of saturated vapor at the absolute pressure P . Over our pressure range this formula departs from the tables by only 0.2%. We may therefore write to a good (1.2%) approximation the following formula:

$$Q = .00216P/D_{vl} \quad (4)$$

where D_{vl} now refers to the specific volume one cubic foot.

A beta-ray source and an ion chamber are herein disclosed to measure steam density. Beta rays are nucleonic emissions identical in action on material as highly-energetic electrons, that is, having a velocity of .3 to .99 that of the velocity of light. They penetrate matter, but are attenuated by a process of gradual degradation of each beta-ray particle. Beta-ray particles of a fixed energy have a fairly well defined maximum range in any material because of this gradual loss of energy. Beta-ray sources emit a whole spectrum of particle energies up to a maximum energy which is the usual energy quoted in the literature.

The absorption by water of radiation from strontium-90 was determined by experiment and is presented in FIG. 6. The transmission is plotted as a function of gms./cm.² of water, that is, weight of a prism of water 1 cm.² in area normal to the radiation. The reading was taken through a 10-mil steel window for reasons to be apparent later. It can be seen from an examination of this curve that water substance absorbs beta radiation rather strongly and that 0.25 gm. of water per sq. cm. will reduce the beta transmission by a factor of 10.

Beta rays will measure only the density of electrons in the material they traverse so that a beta gauge installed in a steam line will measure water density without regard for the state of the water. Typical beta absorptions at the two extremes of measurement may be computed. At 500 p.s.i.g. and 100% quality the density of water is 0.0458 gm. per sq. cm. per inch thickness, so that six inches of this substance would reduce the beta-ray beam by a factor of 13.3. At 300 p.s.i.g. at 50% quality the density is 0.0563 gm. per sq. cm. or the reduction factor is 25.9 per six inches of substance. For example if the beta-transmission reading in the first case was 100 units then the reading in the latter case is 51.3. A 6% decrease in density almost doubles the transmission. It is instructive to consider for a moment that pressure remains constant at 300 p.s.i.g. and that quality varies from 50 to 100 percent. The density varies from 0.0513 gm. per sq. cm. per inch to 0.0282 gm. per sq. cm. The transmission reading changes from 51.3 to 263. The trans-

mission measurement varies by five to one while the density varies two to one. It is apparent from these calculations that this method for measuring density will give adequate dynamic range. It is felt that the transmission needs to be measured to an accuracy of $\pm 2\%$ within one-tenth second. In terms of nuclear statistics this means a registering of 25,000 events per second.

Beta-rays have very little penetrating ability in terms of other nuclear particles such as neutrons or hard gamma rays. This means that the beta-rays will not penetrate the $\frac{1}{2}$ inch steel walls. Hence the beta-ray source and detector must be inside the steam line. The usual sealed strontium sources can be built with a stainless-steel-foil cover and mounted in the steam line, while the beta-rays must be brought out to the detector through a thin wall.

Other objects and features of the invention will hereinafter become more fully apparent from the following description of the annexed drawings, which illustrate a preferred embodiment, and wherein:

FIG. 1 is a block diagram of the steam quality indicator system;

FIG. 2 is a view of the density measuring apparatus as applied to a 6 inch pipe;

FIG. 3 is a cross-section view of the beta-ray source mounted on a pipe;

FIG. 3A is a detail view of the source mount;

FIG. 4 is a cross-section view of the ion chamber mounted on a pipe;

FIG. 5 is a graph of the density of saturated steam in gms./cc. as a function of pressure;

FIG. 6 is a graph of the transmission of strontium-90 beta rays through an .010 inch thick steel window and water;

FIG. 7 is a graph of the moisture content of a given volume of steam versus the logarithm to the base e of the intensity of the beta radiation from a 10 millicurie ruthenium 106/rhenium 106 source with varying steam pressure;

FIG. 8 is a schematic diagram of the log amplifier 18;

FIG. 9 is a graph of the ion chamber response to strontium 90 beta-rays transmitted through water; and

FIG. 10 is a block diagram of the analog computer 20.

Referring now to the drawings, wherein like reference characters designate like or corresponding parts throughout the several views, there is shown in FIG. 1 a pipe 10 carrying the steam whose quality is to be measured. A beta-ray source 12 is mounted at one side of the pipe 10 and emits high speed electrons toward an ion chamber 14 having a window 16.

A log amplifier 18 connected to the ion chamber produces an output proportional to the logarithm of the current through the ion chamber 14, which output is connected to one input of analogue computer 20. A pressure transducer 22 measures the steam pressure in pipe 10 and is connected to a pressure amplifier 24 whose output is connected to another input to computer 20.

The output of the computer 20 is connected to a steam quality recorder 26.

Referring to FIGS. 2 and 3, the beta-ray source 12 is mounted on the pipe 10. A steel source flange 28 is welded to the pipe 10 and extends away at right angles to the pipe to an inside threaded section 30 in which is mounted a support plug 32. A source mount rod 34 is threadedly engaged with support plug 32 so that it may be easily moved in and out and is fixed in a calibrated position by nut 36. A source housing 38 is threadedly attached to rod 34 and holds source mount 40 against the end 42 of rod 34.

Referring also to FIG. 3A, a recess 44 in the end of mount 40 supports a sintered aluminum oxide wafer 46 having a thin layer 48 of strontium-yttrium 90 in the chloride form fused in a sodium silicate glass. A value of 20 millicuries of strontium-yttrium 90 was used in this embodiment.

Since the strontium chloride is soluble in water an .004 inch thick, stainless-steel seal 50 is placed in contact with the strontium glass layer 48 and welded to the mount 40. A ring-shaped gasket 52 having a number of deformable serrations 53 is placed against the seal 50 and held in place by the outer seal disc 54 and housing 38. The inner surfaces of the disc 54 and housing 38 are beveled at 55 to provide an opening for the beta-rays from the layer 48 through the seal 50 into the pipe 10.

Due to the high pressures in the steam line (500 p.s.i.g.) the seal 50, layer 48 and wafer 46 may yield but will not rupture because of the backing of the source mount 40. The complete unit will be subjected to overpressure before actual use.

While the source 12 will normally be pressure tight, a cap 56 is placed over the outer end of the source flange 28 and bolted thereto by bolts 58 and nuts 60 to insure a positive seal and to minimize accidental movement of the rod 34 which changes the calibration of the indicator.

Referring to FIGS. 2 and 4, an ion chamber assembly 70 is shown having a flange 72 welded to pipe 10 diametrically opposite the beta ray source 12. A circular flange 74 has a number of circumferential holes 76 to allow bolts 78 and nuts 80 to clamp an ion chamber housing 82 between flange 74 and flange 72. The ion chamber housing 82 has a central cylindrical section 84 which extends toward the pipe 10 where its end forms a backup plate 86 having a plurality of .187 inch dia. holes 88.

A beta-ray transparent window 16 made of a circular sheet of .0075 inch thick stainless steel is welded to the pipe side of the back-up plate 86 and is further protected by a ring 90 welded at the outer circumference at 92 to window 16 and back-up plate 86.

A Micarta insulator 94 is fastened by screws 96 to the outer end of the cylindrical section 84 of housing 82 to complete the ion chamber. A central anode 98 is fastened by screw 100 to insulator 94 and extends through the ion chamber 14 towards the backup plate 86. A cathode in the form of a tube 102 is fastened by angles 104 and bolts 106 to the insulator 94. Connecting leads 108 are brought out to spark plug type terminals 110 from anode 98 and tube 102.

The ion chamber 14 is filled with a mixture of 98% argon and 2% nitrogen at a pressure of 45 p.s.i.

Strontium 90 has a half life of 22 years and therefore a change in the intensity of radiation of 0.3% per month is to be expected. This small change will allow a recalibration once a month by means of adjusting the source mount rod 34 (FIG. 3) to adequately correct for this minor variation.

Referring to FIG. 1, the pressure transducer 22 uses a Bourdon tube element and is a type No. 145-2 series Pressure Transmitter 0-600 p.s.i.g. made by Manning, Maxwell and Moore, Inc. of Stratford, Conn.

The pressure amplifier 24 is amplifier model K2X made by George A. Philbrick Researches Inc., 285 Columbus Ave., Boston, Mass.

The quality recorder 26 is a type 128T made by the Sanborn Co., Cambridge, Mass.

An alternate beta-ray source 12 using ruthenium 106, which has a beta of 3.5 mev., instead of strontium 90 (2.18 mev.) was considered in the case of a 12 inch pipe. For a 12 inch pipe a source size of 191 millicuries was required at a cost of about \$2,000 which was considered excessive. For a 6 inch distance between the source and ion chamber a source of only 10 millicuries was needed. This 6-inch distance on a 12 inch pipe could be achieved by moving the source mount rod 34 halfway across the pipe.

FIG. 7 depicts a family of pressure lines showing how moisture content varies with the logarithm to base "e" of the beta radiation detected. The standard deviation in $\log_e I$ is .02 due to nuclear statistics. This will give, as illustrated in the diagram, a standard deviation of 1.8%

moisture. Other system errors of statistical nature give a further r.m.s. standard deviation of 1.0% so the total error will be 2.5% approximately or 5% of the 50% moisture value. There will be systematic errors in addition, however these can be eliminated by suitable scale calibration.

Ruthenium has the advantage that it can be plated on the metallic source window resulting in improved structural design over the strontium source which is laid down as a glass. It has a disadvantage however, since it has a half life of one year so that corrections for decay must be made more frequently. It does emit about 30% gamma rays, which will not affect the gauge operation and will not pose a shielding problem in the size contemplated.

From FIG. 7 the function performed will be

$$Q = \frac{BP}{(\ln I_0 - \ln I)} \quad (5)$$

where Q is quality in percent, P is the pressure in p.s.i., $\ln I_0$ —the intensity of the radiation detected through the steam at 100% quality (no entrained water), $\ln I$ —natural logarithm of the radiation intensity detected through the steam and entrained water, and B —a scale factor.

A schematic circuit of the log amplifier 18 is shown in FIG. 8 wherein the ion chamber 14 has its anode 98 connected to a plus voltage and its cathode 102 connected to the plate of diode V_1 and the grid of triode V_2 . The output of tube V_2 from its plate is connected to the input of amplifier 116 (a Philbrick K2X model) having a gain A_1 and an output E_3 . The output of amplifier 116 is connected back to the cathode of V_1 and to one end of R_1 . The other end of R_1 is connected to the input of amplifier 118 (similar to 116) having an output E_0 .

Feedback resistor R_2 is connected across amplifier 118 from the other end of R_1 to E_0 .

The first tube element V_1 is a vacuum diode operated with a negative cold-electrode potential. The electron evaporation from the surface of the hot cathode follows the Maxwellian velocity-distribution law and electron current flows at negative potentials. The relation between this current, i , and diode plate-cathode potential e ($E_3 - E_2$ in FIG. 8) is given by:

$$i = i_s \exp(-qe/kT) \quad (6)$$

where:

q =electronic charge= 1.59×10^{-19} coulombs,

k =Boltzmann constant= 1.372×10^{-23} watt-sec./deg.,

T =absolute temperature of the hot cathode, °K.

e =diode plate-cathode potential and

i_s denotes the saturation current given by the modified Richardson equation:

$$i_s = SAT^2 \exp(-q\phi/kT) \quad (7)$$

where S denotes surface area of hot cathode in cm^2 , ϕ is Richardson's work function, and A is a constant.

If the filament current is fixed, then i_s becomes a constant F , and q/kT becomes a constant m . Then Equation 6 becomes:

$$i = F \exp(-me) = F \exp(m) \exp(-e) = H \exp(-e) \quad (8)$$

or

$$-e = \log i - \log H \quad (8)$$

Proceeding to the amplifier stage represented by amplifier A_1 and electrometer tube V_2 : suppose that the circuit is in a reference condition denoted by prime ('). That is $i = i'$; $E_2 = E'_2$ and $E'_2 - E_{cc} = e'_g$. The current through V_2 , that is $-I_0$, becomes I_p for this state. For all conditions other than the reference condition, I_0 differs from I_p by an increment, i_p . $I_0 = I_p + i_p$.

We may write down the general equation of the input voltage E_1 to A_1 as:

$$E_1 = E_{bb} - R_L (I_p + i_p)$$

The general equation for the output is:

$$E_3 = A(E_1 - E_{KK})$$

We have introduced E_{KK} to accomplish two functions; first to provide the external bias "c" to the Philbrick K2X amplifier so that it will operate as a balanced amplifier and secondly to provide an arbitrary additive constant "d," related to $\log I_0$. Making use of the above relations, we can write:

$$E_3 = A [E_{bb} - (I_p + i_p) R_L - E_{KK}]$$

but $i_p R_L = G_2 (E_2 - E'_2)$ where $-G_2$ is the gain of V_2 . So that:

$$E_3 = A [M - G_2 E_2] \quad (9)$$

$$\text{where } M = E_{bb} - I_p R_L + G_2 E'_2 - E_{KK}.$$

The second amplifier stage A_2 on FIG. 8 provides additional voltage amplification and an adjustable multiplying factor. The output E_0 is given by:

$$E_0 = -AE_3 / 1 + AF_2 \quad (10)$$

The feed-back term

$$F_2 = \frac{R_1}{R_1 + R_2}$$

The output impedance is the open loop impedance of element A_2 (300 ohms) multiplied by:

$$\frac{1}{1 + AF_2} \quad (11)$$

In the particular application it is less than one ohm.

We have postulated that:

$$i = I_0 \exp(-\mu D) \quad (12)$$

where i is ion chamber current, μ is the absorption coefficient for water substance, and D is the steam density. Equation 12 becomes:

$$D = \frac{1}{\mu} (\log I_0 - \log i) \quad (13)$$

The output of the log amplifier $E_0 = -D$. It is negative only for convenience in feeding into the input of the computer. Combining Equations 8, 9 and 10 and noting that $e = E_3 - E_2$, we may write for E_0 :

$$E_0 = \frac{A}{1 + AF_2} \frac{AG_2}{1 + AG_2} \left(-\log H - \frac{M}{G_2} + \log i \right)$$

$$= \frac{1}{\mu} (\log I_0 + \log i) \text{ by Equation 13}$$

$$\therefore \mu = \frac{(1 + AF_2) \cdot 1 + AG_2}{A \cdot 1 + AF_2} \quad (14)$$

$$\log I_0 = \frac{M}{G_2} + \log H \quad (15)$$

Equation 14 becomes:

$$\mu = \left(\frac{1}{A} + \frac{R_1}{R_1 + R_2} \right) \frac{(1 + 1)}{AG_2}$$

For $A = 30,000$, and $G_2 \approx 2$,

$$\mu = \frac{R_1}{R_1 + R_2}$$

So that μ is determined by the setting of R_2 .

Equation 10 becomes:

$$\log I_0 = \log i_s + \frac{q}{kT} + \frac{1}{G_2} (E_{bb} I_p R_L + G_2 E'_2 - E_{KK})$$

The value of $\log I_0$ can then be set by varying E_{KK} , the other parameters being fixed by selected component values.

The amplifier adjustment will proceed as follows: Let us assume that for a six-inch pipe that saturated steam at 505 p.s.i.g. has a density corresponding to $D_{505} = 0.275$ gms./cm.³; let $E_{0(505)} = -25$ volt. Further, the density of saturated steam at 305 p.s.i.g. has a density: $D_{305} = 0.169$ gms./cm.³. This must produce a voltage $E_{0(305)} = -15.4$ volts. Let us assume that we can initially calibrate an installation from steady state temperature and pressure considerations, or alternately from the introduction of

known absorbers between the beta source and the ion chamber in situ. At D_{305} adjust E_{KK} until $E_{0(300)} = -15.4$ volts. Then at D_{505} adjust R_2 so that $E_{0(500)} = -25$ volts. This will change $E_{0(305)}$, so repeat until the output converges to the correct values. Once the initial calibration has been completed, two values of current from an electronic source can be applied to the input. These currents can be used in the above calibration procedure when the calibration or drift of the instrument is checked. If one of these values is set accurately at I_0 , then theoretically, at least, only two adjustments need be made to set up the amplifier.

The proposed mechanism for determining steam quality presupposes that the output of the ion chamber varies in an exact exponential manner as the density of steam and water in the pipe changes. This is only approximately true however. The departure for linearity is demonstrated in FIG. 9 in the curve for water. A straight line covering the range 0.17 gms./cm.² to 0.28 cm.² has been drawn. It satisfies the equation:

$$D = (9.92 - \log I) / 6.76$$

This is an "end-point" line and is not the best straight line. It is the type of working line however which would result in a routine two point calibration. The maximum departure from linearity is about 4%. This is undesirable. However, we may considerably reduce the deviation by using a type of compensated ion chamber. It is noted that the curvature of the experimental curve is concave downward. If we add a fixed amount of current ΔI , then large values of $\log I$ are increased slightly but small values of $\log I$ are increased more so that the tendency is to reduce the curvature or improve linearity. We can add an amount of response current ΔI simply by having a second small strontium source in the ion chamber assembly. Since linearity will vary with the actual fabrication and set up of each assembly, the ion chamber will be built so that the effect of the small source can be adjusted for maximum linearity. Once this adjustment is made it will remain fixed so long as the instrument is used over the same density range.

A block diagram of the analog computer 20 is shown in FIG. 10 where in subtractor 122 the output in I is subtracted from $\ln I_0$. Multiplier 124 multiplies scale factor β times the pressure P and divides this quantity by the output of subtractor 122 to obtain quality Q .

A list of the symbols and definitions as used in the equations unless previously defined are as follows:

Q =steam quality in percent.

M_v =mass of water vapor in a given volume.

M_l =mass of liquid water in a given volume.

D_{vi} =mean density of the water (liquid and vapor) in a given volume.

a =a constant depending on the geometry of a given volume.

B =a constant scale factor.

V_v =volume occupied by the water vapor for a given volume.

V_l =volume occupied by the liquid water for a given volume.

M_{vp} =mass of 100% saturated steam which would fill a given volume.

D_{vp} =the density of 100% saturated steam at the absolute pressure P .

P =absolute pressure of a given volume.

I_0 =the intensity of the radiation detected through dry steam.

I =the intensity of the radiation detected through the steam whose moisture is to be measured.

i =current flowing through diode V_1 of FIG. 8.

F_2 =a feedback term

R_1

$\underline{R_1+R_2}$

The steam quality indicator herein disclosed automati-

5 cally calculates the steam quality continuously despite pressure, temperature, and flow rate variations. The system can be calibrated to be within 5% error while the sampling speed is equal to a system having 10 samples per second. The equivalent sampling speed or accuracy could be increased as high as desired merely by using a higher intensity beta source to increase the number of counts per second required for the statistical accuracy of +2%.

10 It should be understood, of course, that the foregoing disclosure relates to only a preferred embodiment of the invention and that it is intended to cover all changes and modifications of the example of the invention herein chosen for the purposes of the disclosure, which do not constitute departures from the spirit and scope of the invention.

I claim:

15 1. A steam condition indicator comprising radiation transmitting means and receiving means responsive to said radiation for measuring the density of a given volume of steam, pressure transducing means for measuring the pressure of said steam, and computing means connected to said pressure transducing means and to said receiving means for calculating the steam quality.

20 2. A steam quality indicator according to claim 1 and further characterized by said density measuring means comprising a beta-ray generator and an ion chamber having a thin steel window mounted on a perforated back-up plate for withstanding the high pressure steam.

25 3. A steam quality indicator according to claim 1 and further characterized by a recorder connected to said computing means for recording the steam quality from zero to 50% over a period of 2 seconds.

30 4. A steam quality indicator comprising means for measuring the density of a given volume of steam in a pipe comprising a beta-ray source mounted on one side of said pipe and an ion chamber mounted on the other side of said pipe diametrically opposite said beta ray source having an output proportional to the intensity of said beta-rays after passing through said steam; a log amplifier connected to the output of said ion chamber for producing an output proportional to the difference between the logarithm of the intensity of the beta radiation through dry steam and the logarithm of the intensity of the beta radiation through the steam being measured; 35 a pressure transducer connected to said pipe responsive to the pressure in said pipe and producing an output which is a function of the pressure in said pipe; an analog computer connected to said transducer and to said log amplifier for dividing the value of the pressure in said pipe by the output of said log amplifier to produce an output proportional to steam quality; and a recorder connected to the output of said computer for recording the steam quality.

40 5. A steam condition indicator according to claim 4 wherein said computing means solves the equation

$$Q = \frac{BP}{(\ln I_0 - \ln I)}$$

45 60 where Q is the quality in percent, P is the pressure in p.s.i., B is a scale factor, $\ln I_0$ is the natural logarithm of an electrical current proportional to the intensity of radiation detected through the steam at 100% quality, and $\ln I$ is the natural logarithm of an electrical current proportional to the radiation intensity detected through the steam and entrained water.

65 6. A steam condition indicator according to claim 1 wherein said computing means calculates the percentage of moisture content of steam as a function of the natural logarithm of the detected density of the steam.

70 7. A condition indicator for superheated steam comprising radiation transmitting means and receiving means responsive to said radiation for measuring the density of a given volume of steam, pressure transducing means for measuring the pressure of said steam, and computing

means connected to said receiving means and to said pressure transducing means for calculating the steam temperature.

8. Apparatus for determining the quality of confined steam comprising radiation means for producing radiation through said steam, receiving means for producing an output responsive to the intensity of radiation passing through said steam for providing a measure of the density, pressure-responsive transducer means for producing an output indicative of the steam pressure, and computer means coupled to said receiving means and to said pressure-responsive transducer means for calculating the steam quality from said outputs.

9. A steam quality indicator for measuring the condition of a volume of steam flowing in a pipe comprising a beta ray source mounted on one side of the pipe, an ion chamber mounted to detect beta rays from said source transmitted through said pipe, the output of said ion chamber being proportional to the intensity of said beta rays, comparison means connected to said ion chamber for producing an output proportional to the difference between the logarithm of the intensity of the beta radiation through dry steam and the logarithm of intensity of the beta radiation of the steam flowing in the pipe, transducer means for measuring the pressure of the steam in the pipe, and computer means connected to said comparison means and to said transducer means for producing an output proportional to the quality of the steam.

10. Apparatus for the measurement of the condition of steam flowing through a pipe comprising a sealed housing rigidly secured to the pipe, said pipe having a first aperture enclosed by said housing and having a second aperture diametrically opposite thereto, a support mounted in said housing and adjustable to positions of varying distance from said first aperture, a wafer mounted on the side of said support closest to said first aperture and having a coating of beta ray producing material

thereon, seal means mounted on said support between said first aperture and said coating to prevent steam from reaching said coating, beta ray receiving means mounted adjacent said second aperture for producing an output proportional to the beta ray intensity, and comparison means for automatically comparing said output with an output corresponding to a reference condition of steam.

5 11. Apparatus as defined in claim 10 and further characterized by said wafer comprising sintered aluminum oxide and said coating comprising strontium yttrium 90 in chloride form fused in sodium silicate glass.

10 12. Apparatus as defined in claim 10 and further characterized by said beta ray producing material is Ruthenium.

15 13. Apparatus as defined in claim 10 and further characterized by said beta ray receiving means comprising an ion chamber surrounding said second aperture, said chamber being filled with a mixture of argon and nitrogen and having a plurality of holes adjacent said aperture, an 20 anode mounted centrally in said chamber, a cathode in the form of a cylindrical section surrounding said anode in spaced relation thereto, and respective output leads for said anode and cathode, said leads being connected to said comparison means.
